UNITED STATES PATENT OFFICE.

DANIEL HIGHAM, OF PHILADELPHIA, PENNSYLVANIA, ASSIGNOR TO THE HIGHAM ELECTRIC MOTOR COMPANY, OF SAME PLACE.

REGULATION OF ELECTRIC GENERATORS.

SPECIFICATION forming part of Letters Patent No. 374,406, dated December 6, 1887.

Application filed March 2, 1887. Serial No. 229,384. (No model.)

To all whom it may concern:

Be it known that I, DANIEL HIGHAM, a citizen of the United States, residing in Philadelphia, Pennsylvania, have invented certain 5 Improvements in the Regulation of Electric Generators, of which the following is a specification.

The object of my invention is to provide for the automatic regulation of electric generators for the production of a constant current in circuits of varying resistances, due to translating devices which are switched into and out of the circuits.

In the accompanying drawings, Figure 1 is 15 a diagram illustrating one form of my invention, which is intended for the larger sizes of generators. Fig. 2 is a diagram illustrating another form, which is intended for the smaller sizes of machines, and Fig. 3 is a diagram 20 of a modification.

In the construction shown in Fig. 1 the magnets F are wound with two sets of coils, one opposing the action of the other. The coils f, which are in a shunt-circuit around 25 the armature, are the main energizing-coils, while the coils c, which are the regulating-coils, are connected in series with the armature-coils in the working-circuit.

From the brush a extends a conductor, s, 30 with which is arranged to make contact an arm or armature-lever, e, connected to the lead p. An electro-magnet, E, whose coils are in the working-circuit, controls this armature-lever. When this armature-lever e is 35 not attracted by the electro-magnet, a shunt-circuit will be closed around the opposing coils, which are thus cut out of action.

When the current in the working-circuit rises above the predetermined strength, the 40 electro-magnet E will throw the opposing coils c into action by attracting the armature-lever e and breaking the contact at t, thereby reducing the magnetic intensity of the field-magnets. When the magnetic field becomes 45 so reduced as to reduce the current in the working-circuit below the predetermined strength, the armature-lever e of the electro-magnet E will be drawn by the retracting-

spring x to make contact at t, whereby the opposing coils c will be cut out through the short 50 circuit of the conductor s. The magnetic field then being increased again, the current will come up to its normal strength, where it is in this manner maintained constant.

In order that the current generated shall 55 not be pulsatory, the electro-magnetic circuit-breaker above described should be so sensitive that the smallest appreciable variation in the working-current would be capable of effecting regulation. The contact at t will then be so 60 rapidly made and broken that the current will be practically continuous. The number of ampère turns in the opposing coils should be such that the full current therein would so 65 reduce the magnetic effect of the shunt-coils that the current of the shunt-coils could not produce sufficient potential at the terminals of the armature (when running at the working speed) to sustain the current of the shunt-coils 70 against the resistance of the shunt-circuit. Under these conditions the electro-magnetic circuit-breaker will be capable of maintaining the current constant with any resistance 75 in the working-circuit up to its maximum resistance.

In the construction shown in the diagram, Fig. 2, the current is maintained constant in substantially the same manner; but in this case, instead of employing opposing coils on the field-magnet, I put all the coils f in series 80 and provide for throwing the entire field-magnet coils into and out of action by means of the electro-magnetic circuit-breaker; but as these coils are the energizing-coils, and not opposing ones, the contact t is placed on the opposite side of the armature e from that shown in Fig. 1. It is not always necessary, however, 85 that the entire field-magnet coils should be cut out. For instance, in cases where the translating devices are never all at one time cut out 90 of the circuits a portion only of the field-magnet coils need be short-circuited, as indicated in Fig. 3, so long as the magnetic field will be reduced sufficiently to check an excess of current when that portion of the coils is 95 cut out.

I claim as my invention—

An electric generator having its field-magnet coils and armature-coils in series in the working-circuit, in combination with a short circuit around said series, field-magnet coils, and an electro-magnetic circuit-breaker in the working-circuit to close the said short circuit.

In testimony whereof I have signed my name to this specification in the presence of two subscribing witnesses.

DANIEL HIGHAM.
